UNITED STATES PATENT OFFICE.

CARLOS N. WEBB, OF LANSINGBURG, NEW YORK, ASSIGNOR TO PERRY D. RANDALL, OF SAME PLACE.

WHIP-SOCKET.

SPECIFICATION forming part of Letters Patent No. 330,448, dated November 17, 1885.

Application filed February 7, 1885. Serial No. 155,184. (No model.)

To all whom it may concern:

Be it known that I, CARLOS N. WEBB, a resident of Lansingburg, in the county of Rensselaer and State of New York, have invented 5 certain new and useful Improvements in Whip-Sockets; and I do hereby declare that the following is a full, clear, and exact description of the invention, that will enable others skilled in the art to which it appertains to make and 10 use the same, reference being had to the accompanying drawings, and to the letters of reference marked thereon, which form a part of this specification.

Similar letters refer to similar parts in the 15 several figures therein.

My invention relates to improvements in whip-sockets, and more particularly to the method of securing rubber disks therein.

The object of my invention is to easily and 20 quickly insert and securely retain a rubber disk in the mouth of a whip-socket.

My invention consists in inserting within a ferrule provided at one end with introverted walls a centrally-perforated elastic disk, preferably of rubber, and one end of a socket-barrel adapted to fit the other end of the ferrule, forcing the barrel into the ferrule until the disk is securely held in position by and between the introverted walls of the ferrule and 25 the end walls of the barrel, one or both of said walls resting in a depression in the face of the disk.

Figure 1 of the drawings is a side elevation of my improved whip-socket. Fig. 2 is a central vertical section of same. Fig. 3 is a side elevation of the barrel with the ferrule removed. Fig. 4 is a top plan view showing the mouth of the socket. Fig. 5 is a central vertical section of the ferrule alone. Fig. 6 is a 40 view in perspective of the rubber disk.

A is a wooden-socket barrel provided with an outer shoulder, A', to present a surface flush with a ferrule placed thereon. C is a rubber disk provided with a central whip-opening, a, and a circular depression, b', surrounding said opening, and forming the circular projecting flange b. The rubber should conform in shape to that of the barrel at its mouth, and when superimposed thereon, as

shown in Fig. 2, project beyond the barrel 50 about equally on every side, being a little larger in diameter than the barrel or the introverted end of ferrule B. The ferrule has its walls bent in at one end, forming the introverted edges g, and at its other end is adapted 55 to receive the open end i of the barrel. The rubber disk is inserted within the ferrule, and preferably before the barrel, and with its depressed side toward the introverted walls of the ferrule, as shown in Fig. 2, the elastic na- 60 ture of the disk permitting of its easy inser- tion through either end of the ferrule. The open end of the barrel is then inserted and forced into the ferrule until the disk is se- curely held in position by and between the in- 65 troverted walls of the ferrule and the end walls of the barrel, the walls g of the ferrule resting in the depression b' in the face of the disk, as shown in Fig. 2.

The parts may be secured in position by 70 rivets D, passing through the barrel and ferrule walls.

It will be readily seen that the disk is se- 75 curely locked in a position from which it can- not be removed by use without tearing apart the projecting flange b, which may be of any desired form or thickness. The depression in 80 the disk may be made on the lower side and adapted to receive the barrel-walls, as shown by dotted lines in Fig. 1.

The uses and general construction of cen- trally-perforated rubber disks in whip-sockets 85 are well known.

The yielding nature of the rubber permits a whip of larger diameter than that of the aperture in the disk to be inserted therein, 90 where it is securely held and prevented from rattling in the socket.

The general form and construction of the 95 rubber disk as I have shown it is old, and I do not claim the same except in combination with other parts.

I am aware that it is not new to hold the rubber disk to the whip-socket by means of a biting-edge on the ferrule and on the barrel, the two edges gripping it between them, or to effect 95 the same object by means of an expansible ring and introverted ferrule or cap; but

What I claim as new, and desire to protect by Letters Patent, is—

The combination, with barrel and introverted ferrule, of a rubber disk having a raised flange, *b*, that extends beyond the barrel, and a depression, *b'*, into which extends the ferrule end *g*, as shown and described.

In testimony whereof I have hereunto set my hand this 6th day of February, 1885.

CARLOS N. WEBB.
